UNITED STATES PATENT OFFICE

2,512,579

DEVICE FOR APPLYING TAPE TO CONTIGUOUS FACES OF RECTANGULAR OBJECTS

George Long, St. Louis Park, Minn., assignor to
General Mills, Inc., a corporation of Delaware

Application February 6, 1948, Serial No. 6,653

12 Claims. (Cl. 216—22)

1

An object of this invention is the provision of an adhesive tape holding and applying device for applying a strip of gummed tape to one or more objects carried along a given path adjacent the device, either by hand or on a suitable conveyor.

Another object of the invention is to provide means for applying Scotch tape or the like to the opposite sides of packages and particularly to taping two or more rectangular cartons together with perhaps a booklet, or the like, secured to the cartons by the same tape.

These and other objects, as hereinafter appear, are accomplished by this invention which is fully described in the following specification and shown in the accompanying drawings, in which:

Figure 1 is a partial top plan view of the taping device as used for placing tape on both sides of a rectangular package as it passes therethrough;

Fig. 2 is a partial perspective on a reduced scale, showing the taping device on the left side omitted for the sake of clearness;

Fig. 3 is a partial enlarged perspective of the arm which applies tape to the package;

Fig. 4 is an enlarged vertical elevation on the line 4 of Fig. 3, showing the mechanism for preventing withdrawal of tape from the taping arm;

Fig. 5 is a section on the line 5—5 of Fig. 1;

Fig. 6 is a partial enlarged perspective taken on the line 6—6 of Fig. 1; and

Fig. 7 is a perspective of a package consisting of two cartons taped together by four strips of tape.

The embodiment illustrated comprises a belt conveyor 10 running over a head pulley 12 keyed on a shaft 14 which is suitably journaled and driven by any suitable means, not shown. The conveyor belt carries spaced clips 20, 22 which separate as they pass around and below at the tail end of the machine (not shown, but which is similar to the pulley 12 at the head end) so that while separated, an operator can set two cartons as C, C' in pairs, as shown in Figs. 1, 2 and 6, so that they can be taped together so as to be sold in pairs, as will now be explained.

At each side of the conveyor belt is a table 30, the table at the lefthand side and its associated parts being omitted for sake of clearness. Above each table 30 are suitably supported two shelves 32, 34, as by means of legs 36, 38 which are located at both the front and rear ends of the shelves. Each shelf, as 34 (Fig. 5), has a stud 40 secured thereto and on this is journaled a two armed lever, one arm 44 of which is con-

2

nected to a spring 46 which tends to hold the end of the arm 44 against a stop 48 on the shelf 34. Within the spring 46 is located a casing 50 in which is slidably fitted a piston 52 which is connected through a rod 54 with the end of the lever 44 to serve as a dashpot to prevent a too rapid return of the arm 44, as will later be understood. The other arm 42 of this same lever carries the adhesive tape, as shown in Fig. 3, and this will be explained in detail.

On the two armed lever 41 is mounted a hub 56 with a tape support 58. A roll of gummed tape, particularly "Scotch tape," 60 rests on the support 58 and is rotatable about the hub 56. This tape comes wound for different sizes of hubs. The hub 56 is accordingly made readily replaceable to suit different sizes of holes in the tape.

Referring now to Figs. 1 and 3, the end of the tape 62 is led off the roll 60 and between a peripherally grooved roller 64 and an eccentric roller 66 rotatably mounted on pins 68 and 70, respectively, on the lever arm 42. The roller 66 carries a lever 72 to the outer end of which is attached a spring 74 so as to normally draw the roller 66 in a clockwise direction. Thus it will be seen that the end of the tape 62 when fed through these rollers will pass readily from right to left in Fig. 3 or toward the conveyor 10 in Fig. 1, but that the eccentric roller will tend to grip it and prevent its withdrawal in the reverse direction. Grooving the roller 64 reduces its tendency to adhere to the adhesive side of the tape. The grooves preferably run peripherally so that the tape will pass smoothly over the roller but could be arranged otherwise.

The end of the tape after passing the metal rollers 64, 66 with the gummed side of the tape toward the grooved roller 64 passes a rubber roller 80 which is rotatably mounted on a pin 82 secured to the arm 42. Further on a rubber roller 84 is similarly mounted on a pin 86 also carried by the arm 42 but the latter roller is set back from the roller 80 somewhat for a purpose which will later be explained. The extreme end of the tape 63 extends beyond the roller 80 when severed, as will also later be explained, and the parts are in the position shown in Fig. 1 when two cartons as C, C' are moved up into contact with the ends 63 of the gummed tape.

It will be observed in Fig. 2 that there are preferably two spaced rolls of gummed tape to be applied to the righthand side of the cartons to be taped and, as shown in Fig. 1, two more rolls of gummed tape 60a are preferably applied

at the same levels so as to balance the strips received from the rolls of Fig. 2, all as shown in Fig. 7.

Assuming now that the parts are in the positions shown in Figs. 1 and 2 with the carton C just engaging four ends of gummed tape at different points, two at each side of this carton. As the carton advances the pressure is applied by the rubber roller 80 at the same time the spring 46 becomes stretched and this roller gradually travels toward the outside of the carton, pressing the gummed tape around the corner of the carton and along its outside. As this happens the rubber roller 84 engages the extreme end 63 of the strip and presses it directly into contact with the carton as it follows the general action of the rubber roller 80. As the rubber roller 84 passes around the corner of the carton, the rubber roller 80 is lifted, as shown in dotted lines in Fig. 1, and the roller 84 only is in contact with the tape. As the taped cartons advance, the foremost carton C engages a roller 90 which operates a "micro-switch" 92 (Fig. 6) which is connected in series circuit with a solenoid 94 and thence to a source of alternating current supply 96. This closing of the switch 92 energizes the solenoid 94, drawing its core 93 inwardly and causing a knife 100 slideable in a bracket 99 to pass between the rubber rollers 84, severing the gummed tape at the point 63, thereby permitting the spring 46 to return the arm 42 from the dotted line position of Fig. 1 to the full-line position as soon as the roller 84 passes the carton C'. The bracket 99 carries a guard 101 which is preferably a transparent plastic. At the same time the dashpot plunger 52 prevents the arm 42 from going back at a too rapid rate.

While Fig. 6 shows only a single solenoid connected to the "micro-switch" 92, it will be understood that the solenoids of the arrangement shown in Figs. 1 and 2 will preferably be placed in parallel so that they will all be operated simultaneously on closing the "micro-switch" 92. The pressure required to operate the roller 90 is counter-balanced by the guides 102 of Fig. 1 which, together with the guides 104, serve to properly align the cartons as they pass through the machine.

In Fig. 7 the gummed strips 110, 112, 114 and 116 are preferably set opposite each other. It will be understood that various arrangements may be used for certain purposes. Under some circumstances one tape strip in the center on each side might be sufficient. In Fig. 7, however, applicant has shown a booklet B which may be sold with the two cartons and secured thereto by means of these gummed strips.

Another very important use for a single strip applying unit is that it may be used alone to apply a gummed strip to a package which the operator holds in his hand as he wipes the package past the device, forcing over the lever 42, and applying the gummed tape to the package, the knife 100 serving as before to sever the gummed strip so that the gummed strip may be thus applied by a single rapid wiping action of the package past the gummed strip applying device.

For some purposes it may be advisable to use, instead of the switch 92 and roller 90, a foot-controlled switch of a type known to the art so that the operator may vary the length of the strip applied at will.

While I have shown and described but a few

embodiments of my invention, it is to be understood that it is capable of many modifications. Changes, therefore, may be made which do not depart from the spirit and scope of my invention as disclosed in the appended claims.

I claim as my invention:

1. A taping device of the class described comprising means for propelling an object to be taped along a given path, an arm normally extending into said path and pivotally and yieldably mounted at the side of said path, the arm carrying two rollers near its outer end, the outer roller being set back so that the inner roller only contacts the tape until said inner roller passes around the corner of the object when the outer roller contacts the end of the tape pressing it against the object and thence around the corner of the object pressing the tape into contact with the side of the object, means for feeding adhesive tape to said arm so that the adhesive side of said tape contacts the front of said object as it moves along said path causing it to adhere thereto, means for preventing withdrawal of the tape as the arm returns to its initial position, said means yielding as the object advances to press the adhesive side of the tape around the side of the object to cause it to adhere thereto, and means operable by said object for severing the tape after the object has advanced to a predetermined point.

2. A taping device of the class described comprising means for propelling an object to be taped along a given path, an arm normally extending into said path and pivotally and yieldably mounted at the side of said path, the arm carrying two rollers near its outer end, the outer roller being set back so that the inner roller only contacts the tape until said inner roller passes around the corner of the object when the outer roller contacts the end of the tape pressing it against the object and thence around the corner of the object pressing the tape into contact with the side of the object, means for feeding adhesive tape to said arm so that the adhesive side of said tape contacts the front of said object as it moves along said path causing it to adhere thereto, means for preventing withdrawal of the tape as the arm returns to its initial position, said means yielding as the object advances to press the adhesive side of the tape around the side of the object to cause it to adhere thereto, and a knife movable between said rollers and operable by said object for severing the tape after the object has advanced to a predetermined point.

3. A taping device of the class described comprising means for propelling an object to be taped along a given path, an arm normally extending into said path and pivotally and yieldably mounted at the side of said path, means for carrying a roll of Scotch tape on said arm and concentrically with its axis, means for feeding Scotch tape to said arm from the roll so that the adhesive side of said tape contacts the front of said object as it moves along said path causing it to adhere thereto, said means yielding as the object advances to press the adhesive side of the tape around the side of the object to cause it to adhere thereto, and means operable by said object for severing the tape after the object has advanced to a predetermined point.

4. A taping device of the class described comprising means for propelling an object to be taped along a given path, an arm normally extending into said path and pivotally and yieldably mounted at the side of said path, tape-

engaging means on said arm, means for feeding adhesive tape to said arm so that the adhesive side of said tape contacts the front of said object as it moves along said path causing it to adhere thereto, said means yielding as the object advances to press the adhesive side of the tape around the side of the object to cause it to adhere thereto, means carrying the tape on the arm and a knife operable by a solenoid energized through a switch closed by said object for severing the tape after the object has advanced to a predetermined point.

5. A taping device of the class described comprising means for propelling an object along a path, an arm pivoted at the side of the path normally extending into said path and carrying two tape engaging members, means for carrying a roll of tape on the arm and concentric with its axis to feed tape between the object and engaging members, and tape cutting means severing the tape between the two tape engaging members so that the outer member will engage the end of the tape when it contacts the object.

6. A taping device of the class described comprising means moving a rectangular object along a path, an arm pivoted at the side of the path and resiliently extending into said path, a pair of tape engaging members on the arm, the outer engaging member being set back of the inner so that the inner member will first contact the object as it moves along the path, means feeding tape between the object and the tape engaging members, and a reciprocable knife actuated at a predetermined position of the object along the path and moving between the two tape engaging members to sever the tape therebetween so that the outer engaging member will press the end of the tape against the rectangular object.

7. A taping device of the class described comprising means for moving an object to be taped along a given path, a pivotal arm having one end yieldably extending into said path to press the tape against the object, means providing a source of gummed tape to the arm, a roller carried by the arm along which the gummed face of tape passes, the roller being grooved to prevent the gummed tape from adhering thereto, and means clamping the tape against the roller to prevent withdrawal as the tape is pulled away from the end and releasing the tape as it is pulled toward the end to be applied to the object.

8. A taping device of the class described comprising means for propelling an object along a path, an arm pivotally and yieldably mounted and extending into said path, tape engaging means at the outer end of the arm to press the gummed face of the tape against the object, means supplying tape to the engaging means, a roller carried by the arm and having peripheral grooves cut on the surface thereof to prevent the gummed tape from adhering thereto, and means clamping the tape against the roller to prevent withdrawal of the tape as it is moved away from said tape engaging means, and re-

leasing the tape as it is moved toward said engaging means and applied to the object.

9. A taping device of the class described comprising means for propelling an object along a given path, an arm normally extending into said path and carrying two tape engaging members, the outer member being set back from the inner member, the inner member first contacting the face of the object and passing around the corner to the side of the object to cause the outer roller to move against the face of the object, press the end of the tape against the object and then pass around the corner to the side of the object, and means for feeding the tape to said arm so that the adhesive side of the tape contacts the object.

10. A taping device of the class described comprising means for moving a rectangular object along a given path, an arm resiliently extending into said path and carrying tape engaging rollers, the outer roller being set back from the inner roller, the inner roller first contacting the face of the object pressing the tape thereagainst and passing around to the side to have the outer roller contact the end of the tape on the face of the object, and means for feeding tape into the path of the object between the object and the rollers.

11. A taping device of the class described comprising means for propelling an object along a given path, an arm resiliently held in said path and having tape engaging means on the end, means on the arm holding the tape end between said engaging means and the object, means for severing the tape while the object is opposite the arm, and means for retarding the return of the arm to its position in the path after the object has passed.

12. A taping device of the class described comprising means for propelling an object along a given path, an arm pivotally and normally extending into said path and having tape engaging means on the outer end, means urging the arm into said path, means carried by the arm for holding the end of the adhesive tape between the tape engaging means and object to be pressed against the object as it moves against the yieldable arm, means for cutting the tape while the arm is displaced by the object, and a dash pot attached to the arm and allowing it to be moved freely by the object but retarding the return of the arm as said urging means returns it to normal position.

GEORGE LONG.
